Inventor,

Horace V. Scott
By *Geo. W. Strong*.

UNITED STATES PATENT OFFICE.

HORACE V. SCOTT, OF SAN FRANCISCO, CALIFORNIA.

REFILLED-BOTTLE DETECTOR.

SPECIFICATION forming part of Letters Patent No. 732,592, dated June 30, 1903

Application filed March 26, 1903. Serial No. 149,507. (No model.)

To all whom it may concern:

Be it known that I, HORACE V. SCOTT, a citizen of the United States, residing in the city and county of San Francisco, State of California, have invented an Improvement in Refilled-Bottle Detectors; and I hereby declare the following to be a full, clear, and exact description of the same.

My invention relates to a device which is designed to expose the refilling of bottles.

It consists of the parts and the constructions and combinations of parts which I will hereinafter describe and claim.

Referring to the accompanying drawings, Figure 1 is a vertical section of a bottle, showing my invention. Fig. 2 is a front view of the casing or cover. Fig. 3 is a side view of the same. Fig. 4 is a front view of the lettered plate with the cover removed. Fig. 5 is a side view of the same. Fig. 6 is a sectional detail showing a part of the bottle-neck with the stopper in position.

It is desirable to prevent the surreptitious filling of bottles or packages containing certain well-known and popular classes of goods, and many devices have been constructed having for their object the prevention of refilling the bottles.

My invention is designed to expose the refilling of bottles if it takes place.

As shown in the accompanying drawings, A represents a bottle of any description.

2 is a plate which is preferably made, as shown, of a folded sheet of aluminium stamped with the word "Refilled" or equivalent character. The bight or fold of this sheet may be fixed to the bottle by suitably-twisted or other wires 3, the ends of which may be cast into the bottle or connected with a flat piece, ring, or loop 4, which will be blown into the glass when the bottle is made, thus preventing the removal of the plate 2.

5 is a hollow or box-shaped piece made open at the lower end and so made as to slip over the ends of the part 2 when they have been closed together. The normal condition of the parts 2 is to separate by reason of the elasticity of the metal, as shown in Fig. 5. These parts being closed together and the outer casing 5 being slipped over the closed parts, the letters or characters marked upon the parts 2 will be concealed from view. This is

effected before the bottle is cast and connected with the part 2. From the upper end of the part 5 twisted wires 6 extend to near the neck of the bottle. From this point these wires are separated, as at 7, so as to extend upwardly at approximately equal distances apart, and the upper ends are provided with backwardly-turned barbs, as shown at 8.

When the bottle has been filled with the liquid, the cork is introduced between the barbs 8 of the wires 7 and seated, and the barbs will then engage the sides of the cork, so that whenever the cork is removed it will draw the casing 5 off from the fixed marked portion 2, so that the released ends will immediately separate, and the words or characters indicating that the bottle has once been emptied will be exposed. It will not be possible thereafter to restore the parts to their normal condition, and thus any refilling of the bottle will be exposed at once.

Having thus described my invention, what I claim, and desire to secure by Letters Patent, is—

1. A device for indicating that a bottle has been opened, consisting of a plate permanently connected with the bottle in process of blowing the latter, said plate having words or characters marked thereon, an inclosing sheath fitting said plate, a stopper, and connections between said sheath and the stopper of the bottle whereby the sheath will be removed and the marked plate exposed when the bottle is opened.

2. A device for indicating that a bottle has been opened consisting of a folded elastic plate, the free ends of which will separate when released, said plate having words or characters marked thereon to indicate that the bottle has been opened, a sheath adapted to inclose said plate when the ends have been pressed together and to conceal the characters thereon, a stopper, and connections between said sheath and the bottle-stopper whereby the removal of the latter withdraws the sheath and exposes the marked plate.

3. A device for indicating that a bottle has been opened or refilled consisting of a folded elastic plate, the free ends of which will separate when released, and upon which plate indicating marks or characters are permanently formed, connections between the bight of

said plate and the bottle, a stopper, an in-closing sheath within which the free ends of the indicator-plate are compressed, and the characters concealed, twisted wires extending from the outer ends of said sheath upward to the neck of the bottle, said wires being separated and having backwardly-turned barbs which engage with the stopper when the latter is introduced, and by which the sheath is withdrawn when the stopper is removed.

4. In a bottle the combination of a member fixed to and projecting into the bottle and provided with descriptive matter, a second

member movable relative to the first-named member and normally concealing said descriptive matter; a stopper; and means connecting the stopper with the second-named member for effecting the withdrawal of said second member with the cork and thereby exposing the descriptive matter of the first-named member.

In witness whereof I have hereunto set my hand.

HORACE V. SCOTT.
